UNITED STATES PATENT OFFICE

HULDREICH EGLI, OF BALTIMORE, MARYLAND

SURFACE CONDITIONER

Application filed December 20, 1926. Serial No. 156,058.

My invention relates to a fluid medium conditioner whereby a predetermined condition in a given medium may be maintained substantially uniform in practically a continuous process. It consists primarily in passing a given medium through a device provided with means whereby a desired agent, or agents, may be added to that medium. Or conversely, absorptive, adsorptive, or catalytic agents of a known affinity may take the place of the addable agents above referred to so that an undesired substance or substances may be removed from the medium. My invention also contemplates reconditioning of these agents by the removal therefrom of the element, or elements, that they have abstracted from the aforesaid medium, and this may be done by either chemical or physical means. Instead of being reconditioned it is within the purview of my invention to bodily remove these agents from the apparatus.

From the foregoing it is apparent that the uses to which this invention may be put are many. While primarily intended for dehydrating air in order to deliver air of a predetermined condition suitable for a given use, it is obvious that it may be equally as well used to control conditions generally where a uniform and constant supply of a gas, vapor, or other fluid medium of a given character is necessary or desirable. It furthermore contemplates the control of condition, not only of contact, but of temperature as well, since the proper temperature is often as vital to a given process as the presence of certain constituent elements.

In the accompanying drawings, which forms a part of this specification, is shown, more or less diagrammatically a device which employs my invention in the treatment of air so that air definitely controlled as to moisture and temperature is continuously discharged from the delivery end of the apparatus.

In said drawings, in which the same reference character refers to the same element in each of the several views—

Fig. 1 is a side elevation, parts being partially cut away to show the internal structure,

Fig. 2 is a plan view, also showing certain parts partially cut away, and

Fig. 3 is a transverse, vertical cross-section showing more in detail the structure indicated in Fig. 1.

Referring more specifically to the drawings, 10 is a casing in which is housed a circular carrier 11, serving as an endless conveyor, to be fully described later, mounted to rotate on hollow trunnions 12 which are held stationary in bearings 13 provided at the top of frame standards 14. To the stationary trunnions on the inside of the carrier is mounted rigid yoke 35. This yoke 35 serves as a support to hold rigid the compartment divisions on the inside of the carrier, also as a stiffener for standards 14. The carrier 11 is divided into compartments, for a reason which will appear later, and the driving mechanism is provided with suitable means to give an intermittent or step by step movement, which in the drawings are shown as Geneva-movements 15 driven from a motor 16 by suitable transmission means indicated in a general way by numeral 17. Motor 16 also serves to drive a fan, not shown, mounted in casing 18. This casing discharges air or other medium forced into it by the fan therein into medium compartment 36, through medium inlet ports 19 which are controlled by louvers 20, through carrier compartments 21 into medium compartment 37, thence again through carrier compartments 21, and finally through ports 41 and through tempering compartment 24.

It is evident when a product is to be of uniform consistency with the ingredients at variance, the process is to be adjusted accordingly, for which reason medium compartment 36 is provided with by-pass port 39 which port 39 is controlled by suitable by-pass damper 40, medium inlet ports 19 are also provided with suitable louvers 20 as heretofore described, the medium outlet ports 41 are also provided with suitable louvers 25, to be fully described later. By-pass damper 40, medium inlet louvers 20 and medium outlet louvers 25 are adjustable and can be operated either individually or simultaneously by means of suitable mechanism 42, which

mechanism 42 is actuated by means of control lever 34. Fig. 1 shows the medium inlet louvers 20 and medium outlet louvers 25 not exactly wide open while medium by-pass damper 40 is restricting the opening of medium by-pass port 39, which indicates when in this position not all of the medium forced into chamber 36 will have to be modified by modifying agents, but a portion of unmodified medium will pass through by-pass port 39 and mingle again with modified medium in tempering chamber 24.

Carrier 11 is in fact, a rotatable segmental carrier, provided with compartments adapted to hold materials capable of modifying air or other medium passing through the apparatus. The holding means may be in the form of trays, tubes, or racks for adsorbent or absorbing material. One of the compartments is indicated at 21 in which are mounted the receptacles 22 for the modifying means, which receptacles are held firmly by suitable means between the inner and outer periphery, 23 and 43, of the carrier. It is understood that the number of compartments 21 may be varied as conditions may dictate. The air or other medium undergoing modification having been acted upon by the materials in receptacles 22 passes into the tempering compartment 24 through ports 41 which are controlled by suitable louvers 25, thence over the tempering coils 26, to be delivered to any desired point.

Some reconditioned air, or other medium, is passed from chamber 27 through flue 28 and a suitable duct (not shown) to port 32 of the outer portion of reconditioning chamber 30, and tempered air is transmitted from tempering chamber 24 by a suitable duct (not shown) to port 33 of the outer portion of reconditioning chamber 31. From these outer portions of the reconditioning chambers the reconditioned and tempered air passes through receptacles 22 to the inner portions of said chambers 30 and 31, these being commingled through port 45, (Fig. 3).

The air passing through receptacles 22 tends to cool the hot agents and consequently will recondition same for the next cycle.

In the partition 44 between the inner reconditioning chambers 30 and 31 are placed openings 45 of proper size to let a corresponding amount of air pass from the inner reconditioning chamber 31 into inner reconditioning chamber 30. In partition 47 which separates reconditioning chamber 30 from heating compartment 29a is placed air conduit to heater 29.

Outer reconditioning chamber 30 is formed by partitions 44 and 47, (see Fig. 3), while reconditioning chamber 31 is formed by partitions 43 and 44. 46 is in effect a continuation of partition 47 and serves to prevent ingress from chamber 37 to heating compartment 29a.

The air passing through receptacles 22 in reconditioning chambers 30 and 31, in reconditioning the agent, becomes correspondingly heated and in passing through air conduit 48 to heater 29 is used either for combustion or being superheated by heater 29 serves to carry off or liberate the constituents from the agent into hood 27 hence through flue 28.

The screen 49 over the heater serves as a measure of protection against possible combustion due to its cooling effect.

Casing 10 is provided on its top with a hood 27 having a flue 28 at its top and an opening at its base of substantially the same size as compartment 21. Directly underneath this hood 27 is a heating chamber 29a in which is a heater 29, which may be heated by hot air, steam, gas or electricity, the function of the heater being to drive off the absorbed or adsorbed material from agents in receptacles 22. The material driven off from said agent, if so desired, may be either collected or expelled after leaving flue 28. Casing 10 is also provided with reconditioning chambers 30 and 31 referred to above, in which matter necessary to a given process may be added to the materials in receptacles 22, the same being delivered to chambers 30 and 31 through ports 32 and 33.

It is believed the foregoing description fully sets forth the operation of my invention. It is to be noted that my invention is capable of application to all those technical and industrial processes that demand for their most effective operation a stable condition of air or other medium, and is especially valuable in dairies, cheese-factories, dyeing establishments, abattoirs, hospitals, laundries, photographic film manufacture, enameling works, blast furnaces, textile industries, theatres, etc., because of the capacity of the apparatus to modify the condition of the air, or other medium, passing through the modifier by reason of the possible variation in speed of the carrier conveying the modifying agent, and the adjustable character of the dampers through which the air is passed over the modifying agent. Furthermore, the control is enhanced by the tempering coils after the predetermined chemical, or chemico physical, character of the air has been effected.

Having thus fully described my invention, what I claim as new and desire to secure by United States Letters Patent is:

1. In a fluid medium conditioner the combination of a housing provided with an intake port, a by-pass port, a discharge port, means for controlling said ports, a movable carrier for a modifying medium, and means for positively and automatically bringing portions of said carrier into the path of the medium being modified.

2. In a fluid medium conditioner the combination of a housing, having an inlet port, a by-pass port and a discharge port for a me-

dium to be modified, a movable carrier for a modifying medium, and means for positively and automatically bringing portions of said carrier into the path of the medium to be modified and for removing it from said

5 path after a predetermined period of time.

3. In a fluid medium conditioner the combination of a housing having an inlet port, a by-pass port and an outlet port for a medium to be modified, dampers controlling said 10 ports, a circular carrier mounted to rotate within said housing, said carrier being provided with means for bringing a modifying agent into the path of the medium to be 15 modified, and means for positively rotating said carrier step by step.

4. In a fluid medium conditioner the combination of a housing having damper controlled intake by-pass and exit ports, means 20 for forcing a medium through said ports and said housing, a rotating carrier mounted within said housing, partially within the path of said medium, means for positively rotating said carrier step by step, said carrier having compartments for an adsorptive medium modifying agent, a modifying agent in said compartments and means for removing adsorbed matter from said agent.

5. In a fluid medium conditioner, the combination of a housing having damper-controlled intake by-pass and discharge ports, means for forcing a medium through said housing and ports, a carrier mounted to move in said housing in the path of said medium, means for causing said carrier to move positively step by step, compartments in said carrier adapted to hold an adsorptive agent to modify the medium passing through the housing, such an agent in said compartments, and a heater to remove from said agent matter adsorbed from said medium.

6. In a fluid medium conditioner, the combination of a housing having damper-controlled intake by-pass and discharge ports, 45 means for forcing a medium through said housing and ports, a carrier mounted to move in said housing in the path of said medium, means for causing said carrier to move positively step by step, compartments in said carrier adapted to hold an adsorptive agent to modify the medium passing through the housing, such an agent in said compartments, a heater to remove from said agent matter adsorbed from said medium, and 50 means for reconditioning the adsorptive agent.

7. In a fluid medium conditioner, the combination of a housing having controlled intake by-pass and discharge ports, means for 60 passing a medium through said housing and ports, a carrier mounted to move in said housing in the path of said medium, means to cause said carrier to move positively step by step, compartments in said carrier adapted to hold an adsorptive agent to modify the

medium passing through the housing, such an agent in said compartments, means to remove from said agent matter adsorbed from said medium.

8. In a fluid medium conditioner, the combination of a housing having controlled intake by-pass and discharge ports, means for passing a medium through said housing and ports, a carrier mounted to move in said housing in the path of said medium, means to cause said carrier to move positively step by step, compartments in said carrier adapted to hold an adsorptive agent to modify the medium passing through the housing, such an agent in said compartments, means to remove from said agent matter adsorbed from said medium, and means for reconditioning the adsorptive agent.

9. In a fluid medium conditioner, the combination of a housing having controlled intake by-pass and discharge ports, means for passing a medium through said housing and ports, a carrier mounted to move in said housing in the path of said medium, means to cause said carrier to move step by step, compartments in said carrier adapted to hold an adsorptive agent to modify the medium passing through the housing, such an agent in said compartments, means to remove from said agent matter adsorbed from said medium, and means for tempering the discharged medium.

10. In a fluid medium conditioner, the combination of a housing having controlled intake and discharge ports, means for passing a medium through said housing and ports, a carrier mounted to move in said housing in the path of said medium, means to cause said carrier to move step by step, compartments in said carrier adapted to hold an adsorptive agent to modify the medium passing through the housing, such an agent in said compartment, means to remove from said agent matter adsorbed from said medium, means for reconditioning the adsorptive agent, and means for tempering the discharged medium.

11. In a medium conditioner, the combination of a housing having controlled intake, by-pass, and discharge ports, means for forcing a medium through said housing and ports, a carrier horizontally mounted and adapted to move in said housing in the path of said medium, a drive means for said carrier including a Geneva movement to cause it to move step by step, compartments in said carrier adapted to hold an adsorptive agent to modify the medium passing through the housing, a modifying agent in said compartments, and means to remove from said agent matter adsorbed from said medium.

12. In a medium conditioner, the combination of a housing having damper-controlled intake, by-pass, and discharge ports, means for forcing a medium through said

housing and ports, a carrier horizontally mounted for rotation in said housing in the path of said medium, means for causing said carrier to positively move step by step, means 5 on said carrier to hold an absorptive reconditioning agent, such an agent in said compartments, a heating chamber, a heater therein adapted to remove adsorbed matter from said agent, a series of reconditioning chambers, through which said agent is adapted to 10 pass, and means for affording communication between the first of said reconditioning chambers and said heating chamber.

13. In a fluid medium conditioner the combination of a housing having an inlet port, 15 a by-pass port and an outlet port for a medium to be modified, dampers controlling said ports, a circular carrier mounted to rotate within said housing, said carrier being 20 provided with means for bringing a modifying agent into the path of the medium to be modified, and means for positively rotating said carrier.

14. In a fluid medium conditioner the combination of a housing having damper controlled intake by-pass and exit ports, means 25 for forcing a medium through said ports and said housing, a rotating carrier mounted within said housing partially within the path 30 of said medium, means for positively rotating said carrier, said carrier having compartments for an absorptive medium modifying agent, a modifying agent in said compartments and means for removing adsorbed matter 35 from said agent.

15. In a fluid medium conditioner, the combination of a housing having damper-controlled intake by-pass and discharge ports, means for forcing a medium through 40 said housing and ports, a carrier mounted to move in said housing in the path of said medium, means for causing said carrier to move positively, compartments in said carrier adapted to hold an absorptive agent to 45 modify the medium passing through the housing, such an agent in said compartments, and a heater to remove from said agent matter adsorbed from said medium.

16. In a fluid medium conditioner, the combination of a housing having damper-controlled intake by-pass and discharge ports, means for forcing a medium through 50 said housing and ports, a carrier mounted to move in said housing in the path of said medium, means for causing said carrier to move positively, compartments in said carrier adapted to hold an absorptive agent to 55 modify the medium passing through the housing, such an agent in said compartments, a heater to remove from said agent matter adsorbed from said medium, and means for reconditioning the absorptive agent.

17. In a fluid medium conditioner, the combination of a housing having controlled 60

intake by-pass and discharge ports, means for passing a medium through said housing and ports, a carrier mounted to move in said housing in the path of said medium, means to cause said carrier to move positively, compartments in said carrier adapted to hold an absorptive agent to modify the medium passing through the housing, such an agent in such compartments, and means to remove from said agent matter adsorbed from said 75 medium.
